CLAIM

The ornamental design for a sanitary thumb-plate guard, as shown and described.

DESCRIPTION

FIG. 1 is a back perspective view of the sanitary thumb-plate guard of the present invention;

FIG. 2 is a front perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and

FIG. 9 is an environmental view illustrating the sanitary thumb-plate guard secured to a thumb of an individual; and, FIG. 10 is an environmental view illustrating the sanitary thumb-plate guard secured to a thumb of an individual which is in contact with a plate.

The portions of the Figures illustrated in broken lines form no part of the claimed subject matter.

1 Claim, 9 Drawing Sheets
